UNITED STATES PATENT OFFICE.

JOHN LENARD STUART, OF OAKLAND, CALIFORNIA, ASSIGNOR TO STUART MACHINE CO., OF SAN FRANCISCO, CALIFORNIA, A CORPORATION OF CALIFORNIA.

COMBINED FOLDING SLEEPING-COT, AUTOMOBILE-COT, AND LITTER.

1,264,574.

Specification of Letters Patent. Patented Apr. 30, 1918.

Application filed July 30, 1917. Serial No. 183,417.

To all whom it may concern:

Be it known that I, JOHN LENARD STUART, a citizen of the United States, residing at Oakland, in the county of Alameda and State of California, have invented certain new and useful Improvements in Combined Folding Sleeping-Cots, Automobile-Cots, and Litters, of which the following is a specification.

10 My invention relates to the class of cots, especially adapted, by reason of folding into small compass, to be conveniently carried about and transported.

15 The object of my invention is to provide a cot of this class which is adapted for use as an ordinary sleeping cot or a cot capable of being fitted upon and between the seat backs of an automobile, or finally for use as a litter, said cot being foldable into small 20 compass for transportation, readily unfolded again for use, and when unfolded being rigid in its frame, and capable of safely bearing its occupant without danger of collapsing, whether under normal conditions 25 of sleeping or of being carried by bearers when used as a litter.

To this end my invention consists in the novel cot which I shall now fully describe, by reference to the accompanying drawings, 30 in which—

Figure 1 is a plan view of my cot, extended for use, part of the canvas or fabric support being broken away.

Fig. 2 is a top view, enlarged, of one of 35 the legs.

Fig. 3 is a side view of the same.

Fig. 4 is a bottom view, enlarged, of the hinge joint of the side-rails, showing it locked.

40 Fig. 5 is a side view of the same, open.

Fig. 6 is a side view of the cot showing it in the act of folding, the canvas support being omitted.

Fig. 7 is a fragmentary view of one end 45 of the cot, with a leg flexed and folded down on the side rails, which are being brought together; the canvas being omitted.

Fig. 8 is a side view of the cot showing the attachment to one of the legs of the adjustable foot rests adapting the cot for use 50 in an automobile.

1 are the side rods or rails of the cot, and 2 is the canvas or other fabric support secured to the rails. The side rails midway of 55 their length, are jointed for folding. The

hinge is one which automatically locks and holds the joint rigid in the extended position of the rail, as in Fig. 1, but which automatically unlocks the joint in the act of folding the cot, as shown in Fig. 6. The 60 hinge, as best seen in Figs. 4 and 5, comprises a pair of sleeves 3 fitted to the adjacent ends of the rail section, said sleeves carrying overlapping lug-ears 4 pivotally connected by a bolt 5. One of the sleeves 65 rigidly carries a latch arm 6 with a lock head 7, and the other sleeve carries a keeper 8 with which the head of the latch arm engages. The relation of the hinge center and the latch and keeper engagement is such 70 that when the rails are extended, as in Fig. 4, the joint is rigidly locked against pressure imposed upon the cot, so that in this position the side rails are rigid throughout their length. But in folding the rail on the 75 hinge center at 5, the latch arm 6 withdraws its head 7 from the keeper 8, said head swinging out from the keeper about the hinge bolt 5 as a center, as in Fig. 5. The locking and unlocking effect is due to the 80 location of the latch arm and keeper approximately directly under the rails when in their extended or cot form, so that their engagement presents a direct resistance to and support for an imposed weight; and the 85 location of the hinge center inwardly with respect to the latch, adapting the rails to fold in the plane required to withdraw the latch head from the keeper. There are three 90 legs. All are of a general bale like shape as seen in Fig. 3.

9 in Figs. 1 and 6 is the middle leg. Its extremities are pivotally carried on the hinge bolts 5 of the side rail joints, and it is jointed at its middle by a pin 10. Its 95 sections overlap and are locked against breaking upwardly by bevels, as seen at 11 in Figs. 2, 3 and 7. The joint is controlled and rendered rigid or free as desired by means of a sliding keeper 12. The leg may 100 therefore bend or flex at its middle, and by having its extremities pivotally carried on the bolts 5 of the rail joints, it may also fold against the rails as in Figs. 6 and 7.

Near one end of the cot is a leg 13. Its 105 ends are pivotally carried at 14 from brackets 15 fitted on the side rails. This leg is jointed at its middle on a pin 16 and its overlapping portions are controlled by a sliding keeper 17. The leg 13 has the 110

same two folding movements as the leg 9, as seen in Figs. 6 and 7.

Near the other end of the cot is another leg 18, seen particularly in Figs. 2 and 3.

- 5 The extremities of this leg are pivotally carried at 19 on brackets 20 which are slideable on the side rails 1, and are adapted to be fixed in the position to which they may be adjusted, by a screw 21 or other 10 device. This leg 18 is jointed at its middle on a pin 22 and its overlapping portions are controlled by a sliding keeper 23. The leg thus has the two folding movements of the other legs. Laced slits 24, Fig. 1, in the 15 canvas 2 of the cot afford ready access to the slideable brackets 20 of the leg 18, in order to adjust them.

In the leg 18 near each side is a socket 25 into which is adjustably fitted by means of 20 a thumb-screw 26, as seen in Fig. 8, an angle bracket 27. Upon each bracket is adjustably fitted by means of a thumb-screw 28, a foot rest 29 of a size and shape adapting it to fit and rest upon the back of an automobile seat.

When the cot is unfolded to its full functional position, as in Fig. 1, the side rails 1 are separated by their full distance, and are extended to their full length their 30 hinge joints 3 being then locked rigidly. The canvas 2 is stretched taut between the rails for its full length. The three bail-like legs extend downwardly perpendicular to the cot surface, and support the cot, said 35 legs being held rigid by their meeting bevels and their keepers which control their middle joints. The cot may now be used either as a sleeping cot or as a litter, or may be swung like a couch hammock. To use 40 it as an automobile cot, as indicated in Fig. 8, the foot rests 29 are applied to the leg 18 and are adjusted properly as to depth. These foot rests 29 now rest upon the back 30 of the front seat of an automobile, while 45 the rails 1 at the other end of the cot rest upon the back 31 of the rear seat of the automobile. The back of the front seat being lower than the back of the rear seat, the cot is leveled by adjusting the depth of 50 the foot rests 29, and the varying distances between the backs of the two seats of different automobiles is provided for by the sliding adjustment of the leg 18 which carries the foot rests 29.

55 By turning the brackets 27 in their sockets 25, and by turning the foot rests 29 on the brackets, the rests may be separated to a greater distance between them, thereby getting a more extensive bearing 60 on the seat back.

To fold the cot, it is inverted, and after sliding back the keepers of all the legs, the canvas is seized by its middle and drawn upwardly thereby drawing in the side rods 65 toward each other, the legs breaking or

flexing at their middle joints, as seen in Figs. 6 and 7. Then the canvas is rolled down to the rails which are now near together, as in Fig. 7, and the three legs are folded down flat on the canvas and rails. Then the rails are folded on their joints 3 so that they inclose the folded legs and canvas between their sections. In this folding, the foot rests 29 are so manipulated by removal and readjustment as to pack nicely in the bundle.

I claim:—

1. A folding cot comprising side rails; a supporting fabric carried by said rails; hinge-joints in the rails adapting their sections to fold upon each other; means associated with said joints adapted to interengage and rigidly lock the sections of the rails against superimposed pressure when said sections are in extended alinement and to separate in the act of folding said sections; transversely disposed legs between said rails; pivotal connections between the legs and rails adapting the legs to fold on the rails; joints in the legs adapting them to flex and draw the rails toward each other; and means for locking said joints when the legs are extended to hold the rails apart.

2. A folding cot comprising side rails; a supporting fabric carried by said rails; hinge joints in the rails adapting their sections to fold upon each other; a latch upon one member of each hinge joint and a keeper upon the other member with which the latch engages, said latches and keepers being positioned to interengage and rigidly lock the sections of the rails against superimposed pressure when said sections are in extended alinement, and to separate in the act of folding said sections; legs transversely disposed between the rails; pivotal connections between the legs and rails adapting the legs to fold on the rails; joints in the legs adapting them to flex and draw the rails toward each other; and means for locking said joints when the legs are extended to hold the rails apart.

3. A folding cot comprising foldable side rails; a supporting fabric carried by said rails; foot rests associated with one end of the cot; and means for adjusting said rests perpendicularly to the rails and fabric.

4. A folding cot comprising foldable side rails; a supporting fabric carried by said rails; foot rests associated with one end of the cot; and means for adjusting said rests longitudinally of the rails and fabric.

5. A folding cot comprising foldable side rails; a supporting fabric carried by said rails; foot rests associated with one end of the cot; and means for adjusting said rests both perpendicularly to the rails and fabric and longitudinally thereof.

6. A folding cot comprising foldable side rails; a supporting fabric carried by said

rails; transversely disposed jointed and foldable legs carried by the rails; vertically and rotatably adjustable angle brackets carried by one of the legs near one end of the 5 cot; and foot rests removably and adjustably fitted on said brackets.

7. A folding cot comprising foldable side rails; a supporting fabric carried by said rails; transversely disposed jointed and 10 foldable legs carried by the rails; vertically and rotatably adjustable angle brackets carried by one of the legs near one end of the

cot; foot rests removably and adjustably fitted on said brackets; and bracket connections between said leg and the rails adjustable longitudinally on the rails. 15

In testimony whereof I have signed my name to this specification in the presence of two subscribing witnesses.

JOHN LENARD STUART.
